METHOD AND APPARATUS OF REFINING
HYDROCARBON OIL

Walter J. Podbielnik, Chicago, Ill.

Application February 5, 1935, Serial No. 5,059

16 Claims. (Cl. 196—40)

The present invention relates to improvements in processes and apparatus for effecting counter-current contact of fluids and more particularly of partly or wholly immiscible liquids of different densities. It is in part a continuation of my prior applications, Serial No. 476,190, filed August 18, 1930, Patent No. 2,004,011, June 4, 1935, and Serial No. 628,152, filed August 10, 1932, Patent No. 2,003,308, June 4, 1935. The invention will be understood from the following description, illustrated by the accompanying drawings, in which—

Figure 1 is an elevation partly in section of a device suitable for carrying out the invention;

Fig. 2 is a vertical sectional view through the apparatus of Fig. 1 on the section line 2;

Fig. 3 is a detailed sectional view through a portion of the rotor, and

Fig. 4 is a detailed sectional view showing a modified form of surface of the rotor passage of the device of Figs. 1 and 2.

In my prior applications hereinbefore referred to, there are shown devices and processes wherein fluids of different densities are brought into intimate contact with each other and wherein the impelling action of centrifugal force is employed to secure effective contact of the fluids and velocities, capacities and completeness of interaction to an extent not hitherto possible. In accordance with the present invention I am enabled to secure effective counter-current action between liquids of different specific gravities, such liquids being wholly or partly immiscible. As will be readily apparent, the apparatus herein described may also be employed in securing counter-current contact between vapors and liquids.

The processes and apparatus of the present invention may be employed in many types of operations in which it is desired to secure effective contact of liquids. For example, it may be employed where the liquids are intended to react upon each other or upon constituents present in one another, for example, as in the refining of oils with sulphuric acid, alkaline solutions, and the like. It may also be employed in solvent extraction processes, such as the extraction of oils of various types with relatively immiscible solvents such as liquid sulphur dioxide, nitrobenzene, phenol, and the like. It may also be used to effect the dehydration of organic substances and for other purposes wherein interaction or reaction between immiscible liquids is desired. For purposes of illustration, in the accompanying description of the apparatus shown in the drawings, interaction between a petroleum oil fraction

such as naphtha, lubricating oil, or the like, and sulphuric acids has been referred to. It will be understood, however, that such references are for the purpose of illustration and are not to be regarded as limitations upon the processes and apparatus described.

Referring to the drawings, the numeral 10 indicates a suitable supporting frame of cast iron or other material to which is attached a casing 11 of generally cylindrical form, in the form illustrated in the drawings, with its axis horizontal. As shown, the casing 11 may be cast integrally with the frame 10 although, obviously, the casing and frame may be formed separately and secured together in any suitable manner. Within the 15 casing 11 there is provided a rotating element or rotor 12, the construction of which will be more fully hereinafter described. The rotor 12 is attached to a hollow shaft 13, which passes through a suitable stuffing box or sealing device 14, formed, 20 as an extension of one wall of the casing 11. The hollow shaft 13 extends through and is mounted in a bearing 15 at the opposite end of the frame 10 in the casing 11, the bearing 15 likewise being provided with suitable packing or sealing devices. 25 The hollow shaft 13 then opens into a chamber 16, the purpose of which will be more fully herein-after described. At a suitable point, for example, between the bearings and seals 14 and 15, a pulley 17 is mounted on the hollow shaft 13, by means 30 of which the latter, together with the rotor 12, may be rotated at any desired speed.

Upon the rear wall or plate 18 of the rotor 12 there is mounted a spirally-wound strip or sheet 19. The space between the windings of this strip 35 forms a spiral passageway, designated by the numeral 20, which is open at its inner end, the latter being at approximately the axis of rotation of the rotor 12. At the outer circumference of the rotor there is secured to the latter the cylindrical retainer 21, suitably formed as a wall member provided at intervals with openings 22, through which liquid contained in the casing 11 may communicate with the interior of the rotor 12 and with the outer end of the spiral passage 20. 45 In the form shown, the spiral passage 20 is of generally rectangular cross-section.

The front wall or face of the rotor 12 is formed by a removable plate 23 which is provided with grooves 24, cut in the form of a spiral and into 50 which the free ends of the spiral web or coil 19 are closely fitted, the plate 23 thereby closing the spiral passage 20. If desired, a rubber or other suitable packing, as indicated at 25, may be provided in the spiral groove 24 in the remov- 55

able plate 23, if necessary to secure a tight seal. The plate 23 may be secured to the rotor 12 by any suitable means, for example, by screws as indicated at 26.

5 The outer face of the casing 11 is closed by a removable plate 27, which may be secured to the casing by any suitable means, for example, by the hinged bolts 28. The casing 11 is likewise provided with a suitable inlet 29 to which may be connected the supply line for the oil or other like liquid to be supplied to the apparatus. The casing 11 is also provided, preferably at its lowermost point, with a discharge conduit 30, through which discharge of liquid from the apparatus is effected. As shown in the form illustrated, the discharge conduit 30 communicates with an enlarged chamber 31 in which separation of heavy liquid may be effected from the lighter liquid, for example, sulphuric acid and sludge from oil. This chamber 31 is provided at its bottom with an outlet line 32 closed by a valve 33. Within the enlarged chamber 31 there is provided a float 34 which, through a suitable mechanism, such as the compressed air control 25 valve 35 and the air driven piston 36, operates to open the valve 33 and permit the discharge of separated heavy liquid or acid from the enlarged chamber 31 when the level of the separated heavy liquid in the latter exceeds a predetermined point.

As has been indicated hereinbefore, the interior of the spiral passage 20 communicates with the central opening in the hollow shaft 13, the opening in the hollow shaft in turn communicating with the chamber 16. The latter is provided with an outlet connection 37, through which lighter liquid or oil may be discharged from the system. A stationary pipe 38 passes through the outer wall of the chamber 16 and through the central opening of the hollow shaft 13, terminating within the innermost turn of the spiral passage 20 and being provided there with slots as indicated at 39 to permit the feed of heavy liquid or acid into the innermost portion of the spiral passage. At its outer end 40 the pipe 38 is provided with a connection through which the acid or other heavier liquid may be supplied.

In operations involving interaction between liquids, for example, the treatment of a heavy hydrocarbon oil fraction such as a lubricant oil having a specific gravity in the order of 0.8 with sulphuric acid such as is usually employed having a specific gravity in the order of 1.6 to 1.8, difficulties have hitherto been encountered by reason of the density of oil, the density of sludge formation and the character of the sludge formed, the difficulty of settling the mixture to secure separation of the oil, sludge and acid after treatment and the tendency of the mixture to emulsify. In subsequent washing an alkali treatment of the acid treated oil, difficulties are likewise encountered in settling, in the tendency of the mixture to emulsify, in the viscosity of the oil and in the relatively smaller differences in the specific gravity of the oil and the washing liquid. By employing the process of the present invention, these difficulties are substantially entirely avoided and at the same time a continuous operation is secured with a prolonged and effective contact of the oil and the acid or washing liquid.

To illustrate the operation of the apparatus and process, for example, in the treatment of oil of the character hereinbefore referred to with sulphuric acid, the oil to be treated is fed under

a suitable pressure to the casing 11 containing the rotor 12 through the connection 29. The treating liquid or acid is fed through the connection 40 to the stationary pipe 38 and reaches the innermost turn of the spiral passage 20, passing through the slotted openings 39 in the end of the pipe.

The oil and the acid being supplied in the proper proportions, the rotor is rotated at a suitable speed to secure an adequate centrifugal force acting upon the liquids present to cause a continuous outward movement of the heavy liquid or acid through the spiral passage 20. In passing through the spiral passage, the heavy liquid distributes itself in a film or layer upon the inner surface of the outer wall of the turns of the spiral passage-way. The difference in density between the acid or heavier liquid and the oil or lighter liquid is effective, under the centrifugal force supplied, to force the acid outwardly through the spiral passage, while the oil or lighter liquid is forced into the casing under such applied pressure as to cause it to travel in the reverse direction through the spiral passage. The direction of rotation of the rotor may be in either direction and is preferably as shown in Fig. 2, in the direction of a decreasing radius of the spiral passage-way.

The acid or any accompanying sludge or product of treatment is discharged at the outside of the passage-way through the openings 22 in the outer wall 21 of the rotor and enters the casing 11, descending through the outlet connection 30 into the enlarged chamber 31 in which it settles from the oil and accumulates. When the body of heavy liquid or acid and sludge in the chamber 31 reaches a predetermined level, for example, as indicated by the dotted line 41, the operation of the float 34 causes the valve 33 to open to permit the discharge of a portion of the acid and sludge. In regular operation this discharge becomes substantially continuous.

The treated oil, forced into and through the spiral passage-way 20 in the rotor 12 by the pressure under which it is supplied to the system, reaches the innermost turn of the spiral passage and passes out through the opening in the hollow shaft 13 around the pipe 38 and discharges into the chamber in the casing 16, from which it may be withdrawn through the connection 37. If desired, another removal pipe or drain pipe 42 may be provided at the lowermost point in the casing 16, and a suitable gauge column 43 may be provided to indicate the level of liquid therein.

In the form shown in the drawings, the spiral passage-way 20 is shown as of constant pitch throughout and thereby the effective or tangential component of the centrifugal force acting upon the liquids present is substantially constant through the travel of the liquid. If desired, the pitch of the spiral passage 20 may be varied, the spiral passage being either given an increasing or decreasing pitch, in accordance with the results which it is desired to secure; for example, if an increased effective force is to be applied in the outer portion of the spiral passage, for example, to secure a greater force to effect separation of the acid and sludge or heavier liquid components from the oil or lighter liquid components, the spiral passage-way can be given an increased pitch as it approaches the outer edge of the rotor. Similarly, if it is desired that the effective force to secure separation of the liquids involved or to reduce the speed of travel of the heavier liquid components as they approach the

outer passage-way of the spiral, the pitch of the spiral may be decreased toward the outer margin of the rotor.

In an apparatus of the character described, with oil and acid as the liquids employed, an effective rate of rotation of the rotor is in the order of 1200 R. P. M. with a rotor of about 12 inch radius, the pitch of the spiral passage or the increase of radius per turn being about 1.5 inches or varying slightly thereunder. Under these conditions, the length of the spiral passage-way 12 will be approximately 25 feet and if the depth of the passage is in the order of 4 inches, the device will be effective to handle in the order of 500 gallons per minute of oil, assuming a feed of acid of about 10% the amount of oil supplied; that is, about 500 gallons per minute. With a device of these dimensions, operated at about 1200 R. P. M., the effective static head of the oil within the rotor approximates 90 pounds and that of the acid approximates 185 pounds. The oil is supplied to the rotor at a pressure in excess of this effective head, suitably at a pressure of 100 pounds or more and under the conditions set forth, a pressure of supply of the oil in the order of 100 to 125 pounds has been found desirable. The substantially greater density of the acid and the resulting larger force with which it is driven outwardly through the spiral passage causes a rapid and free flow of the acid with respect to the oil. As pointed out hereinbefore, the acid distributes itself over the inner surface of the outside wall of the passage-way in its travel and is intimately contacted at its surface with the oil flowing under pressure in the reverse direction. If desired, as shown with the modified form in Fig. 4, the inner surface of the outer wall of the passage-way 20 may be provided with grooves of any desired form or with other irregularities or projections, so as to cause an internal agitation to improve or increase the extent of contact between the oil and the acid.

In operation, in the event of an obstruction or tendency to form an obstruction in the passage-way, the heavier liquid component tends to build up and accumulate back of the obstruction and thereby makes automatically effective a greater increased outward driving force to remove and dislodge the obstruction. It is to be noted that the power demands for rotation of an apparatus such as that herein set forth are relatively low, since the entering light fluid, under the pressure at which it is supplied, contributes substantially to the force effective for rotation of the rotor in the desired direction.

While the apparatus has been described in connection with specific details of construction and rates of rotation, it is to be understood that these are not essential or critical and that the various factors involved such as the size and rate of rotation of the rotor, the size and pitch of the spiral passage-way and the spacing of the turns forming the spiral passage-way may be varied in accordance with the materials under treatment and the desired result. The rate of rotation is such that the tangential component of the centrifugal force developed, which is effective in securing travel in an outward direction of the heavier component of the system is at a desired value, preferably substantially in excess of gravity. In the operation illustrated and described, it is in the order of ten times gravity and in general, I prefer that it shall be not less than two times gravity and preferably at least four times gravity. With liquid components of the system

that show a tendency to emulsification it is desirable that the effective force be greater than when the liquid components do not tend to emulsify, to facilitate separation of heavy liquid or sludges formed in reaction at or near the outlet of the spiral passage. When the liquid components do not differ greatly in density, it is advisable, by suitably varying the pitch of the spiral passage and rate of rotation, to increase relatively the effective force by which the heavier liquid is driven outwardly.

The device in operation gives a long effective path for interfacial contact between the components of the system and, as indicated hereinbefore, when desired, by slight groovings or projections upon the walls of the passage, either for their entire length or preferably in the intermediate portion of the passage alone, some additional agitation or turbulence can be secured by which even more effective intermingling or contact of the liquids can be secured. When such groovings or projections are provided in the intermediate portion of the passage-way, the end portions are available for securing a more effective separation of the components near their respective points of discharge while still maintaining interfacial contact between them.

It is readily apparent that the process and apparatus may be employed for the continuous counter-current treatment of liquids of different specific gravities for a variety of purposes; for example, for chemical interaction; for solvent extraction, washing or the like. It is likewise apparent that the apparatus disclosed may also be employed for the counter-current treatment of a liquid with a gas or vapor, the latter then following the path of the lighter liquid in the operation as described. Thus, it may be employed in washing of water gas or producer gas or of coke oven gas to remove hydrogen sulphide; for washing or contacting gases with water or other fluids to remove fume, solids or the like, and for interaction between a reactive gas and a liquid, for example, in the chlorination of hydrocarbons. In chlorination or other halogenation reactions, or in other reactions in which a liquid reaction product is secured from the reaction of two or more gases, the gases intended to react with each other may be introduced at the outlet of the spiral passage-way, the liquid reaction product being discharged therefrom on formation. In any case, such as in the latter reactions, in which the presence of actinic light is desired to effect or aid the reaction, the outer face 27 of the casing 11 and the outer wall 23 of the rotor may be constructed in whole or in part of transparent quartz or of a suitable glass or transparent plaster, to permit actinic rays from a suitable source (not shown) to enter the passage-way.

The rotor and other parts in contact with the materials under treatment may be formed of any suitable chemically resistant material adapted for the intended use; such as glass or quartz; suitable stainless steels, such as low chromium and nickel-chromium iron alloys, nickel, Monel metal or the like; or may be plated or coated with suitable chemically resistant materials, such as tantalum, platinum, gold, silver, enamel or the like. Various non-reactive plastics of the phenol-formaldehyde or urea-formaldehyde type may also be employed in forming the parts of the device or as coatings thereon.

I claim:

1. The method of effecting contact between incompletely miscible liquids which comprises

- supplying one of said liquids of greater density to the center of a curved passageway of increasing radius, rotating said passage-way to secure by centrifugal action an outwardly propellant force to propel said liquid outwardly through said passage-way and supplying the lighter of said liquids to the outer end of said passage-way under pressure sufficient to force said lighter liquid inwardly through said passage-way to the center thereof in counter-current contact with said heavier liquid.
2. The method of effecting contact between incompletely miscible liquids which comprises supplying one of said liquids of greater density to the center of a curved passage-way of increasing radius, rotating said passage-way to secure by centrifugal action an outwardly propellant force substantially exceeding that of gravity to propel said liquid through said passage-way, and supplying the lighter of said liquids to the outer end of said passage-way under pressure sufficient to force said lighter liquid inwardly through said passage-way to the center thereof in counter-current contact with said heavier liquids.
3. The method of effecting contact between incompletely miscible liquids which comprises supplying one of said liquids of greater density to the center of a spiral passage-way of rectangular cross-section, rotating said passage-way to secure by centrifugal action an outwardly propellant force to propel said liquid outwardly through said passage-way in a layer adjacent the outer wall thereof, and supplying the lighter of said liquids to the outer end of said passage-way under pressure sufficient to force said lighter liquid inwardly through said passage-way to the center thereof in counter-current contact with said heavier liquid.
4. The method of effecting contact between incompletely miscible liquids which comprises supplying one of said liquids of greater density to the center of a curved passage-way of increasing radius, rotating said passage-way to secure by centrifugal action an outwardly propellant force sufficient to propel said liquid outwardly through said passage-way, supplying the lighter of said liquids to the outer end of said passage-way under pressure sufficient to force said lighter liquid inwardly through said passage-way to the center thereof in counter-current contact with said heavier liquid, and effecting agitation of the heavier liquid in at least part of its travel through said spiral passage-way.
5. The method of effecting contact between incompletely miscible liquids which comprises supplying one of said liquids of greater density to the center of a curved passage-way of increasing radius, rotating said passage-way to secure by centrifugal action an outwardly propellant force sufficient to propel said liquid outwardly through said passage-way, discharging said liquid into a relatively stationary chamber communicating with the outer end of said passage-way, supplying the lighter of said liquids to said chamber and maintaining in said chamber a head or pressure of said lighter liquid sufficient to force said lighter liquid inwardly through said passage-way to the center thereof in counter-current contact with said heavier liquid.
6. The method of effecting contact between incompletely miscible liquids which comprises supplying one of said liquids of greater density to the center of a curved passage-way of increasing radius, rotating said passage-way to secure by centrifugal action an outwardly propellant force sufficient to propel said liquid outwardly through

said passage-way, discharging said heavy liquid into a relatively stationary chamber communicating with the outer end of said passage-way, supplying the lighter of said liquids to said chamber, maintaining in said chamber a head or pressure of said lighter liquid sufficient to force said lighter liquid inwardly through the passage-way to the center thereof in counter-current contact with said heavier liquid, and discharging said lighter liquid centrally from said rotating passage-way.

7. An apparatus for effecting counter-current contact between fluids, a rotor member having a face-plate, a spiral strip mounted on said face-plate, whereby a spiral passage-way is formed thereon, a closure plate forming an opposing face for said rotor, said closure plate being provided with a spiral groove into which the edge of said spiral strip is fitted, means for rotating said member, and means for supplying a fluid to the center of said passage-way to be propelled therethrough by centrifugal force resulting from the rotation of said rotor member.

8. An apparatus for effecting counter-current contact between fluids, a rotor member having a face-plate, said face-plate being provided with a central opening, a spiral strip mounted on said face-plate whereby a spiral passage-way is formed thereon, a closure plate forming an opposing face for said rotor and closing said passage-way, said closure plate being provided with a spiral groove into which the edge of said spiral is fitted, means for supplying a fluid through the central opening of said face-plate to enter the spiral passage-way centrally of the rotor, and means for rotating said rotor member to force said fluid outwardly therethrough by centrifugal force.

9. An apparatus for effecting counter-current contacts between fluids, a rotor member having a face-plate, said face-plate being provided with a central opening, a spiral strip mounted on said face-plate whereby a spiral passage-way is formed thereon, a closure plate forming an opposing face for said rotor and closing said passage-way, said closure plate being provided with a spiral groove into which the edge of said spiral is fitted, means for supplying a fluid through the central opening of said face-plate to enter the spiral passage-way centrally of the rotor, means for rotating said rotor member to force said fluid outwardly through the passage-way by the action of centrifugal force, and means for supplying a lighter fluid to the outer opening of said passage-way under pressure sufficient to force it inwardly therethrough.

10. An apparatus for effecting counter-current contacts between fluids, a rotor member having opposing face-plates, and a spiral strip mounted there between, whereby a spiral passageway is formed in said rotor, one of said face-plates having a central opening communicating with said spiral passageway at the center of the rotor, a hollow shaft on which said last-mentioned face-plate is mounted, the central opening in the face-plate communicating with the opening in said hollow shaft, the other of said face-plates being provided with a spiral groove into which the edge of said spiral strip is fitted, means for supplying a fluid to the center of said spiral passageway, means for rotating the hollow shaft, thereby rotating said rotor and forcing said fluid outwardly through the passage-way by centrifugal force, means for supplying a lighter fluid to said passage-way at the exterior of the rotor

under pressure sufficient to force said lighter fluid inwardly through said spiral passage-way counter-current to the first-mentioned fluid and effecting discharge of said lighter fluid from the center of said passage-way through the opening in said hollow shaft.

11. An apparatus for effecting counter-current contact between fluids, a rotor member having opposing face-plates and a spiral strip mounted there between whereby a spiral passage-way is formed in said rotor, one of said face-plates being provided with a spiral groove into which the edge of said spiral strip is fitted, the other of said face-plates having a central opening, a hollow shaft on which the last-mentioned face-plate is mounted, the opening in said hollow shaft communicating through the central opening of said face-plate with the center of the spiral passage-way in the rotor, a stationary pipe extending through the opening in said hollow shaft and terminating centrally within the rotor, means for supplying a fluid through said stationary pipe to the interior of said rotor, means for imparting rotary movement to the hollow shaft and the rotor to rotate said rotor thereby forcing said fluid outwardly through the spiral passage-way in the rotor under centrifugal force developed by the rotation thereof, and means for supplying a lighter fluid under pressure to the exterior of the rotor passed inwardly through the spiral passage-way therein in counter-current to the first-mentioned fluid, said lighter fluid being discharged through the central opening and the opening in said hollow shaft around said stationary pipe.

12. An apparatus for effecting counter-current contacts between fluids, a rotor member having opposing face-plates and a spiral strip mounted there between, forming a spiral passage-way in said rotor, one of said face-plates being provided with a spiral groove into which the edge of said spiral strip is fitted, the other of said face-plates having a central opening communicating with the center of said passage-way, a hollow shaft on which said rotor is mounted, the opening of said hollow shaft communicating through the central opening of said face-plate with the center of said spiral passage-way, means for supplying a heavy fluid at the interior of said spiral passage-way and means for rotating said hollow shaft and said rotor to force said fluid outwardly through the passage-way by the action of centrifugal force, a casing surrounding said rotor, and means for supplying a lighter fluid within said casing under pressure to cause said lighter fluid to enter the rotor and travel inwardly through the spiral passage therein in counter-current contact with the outwardly traveling first-mentioned fluid, and means for discharging said lighter fluid from the center of said spiral

passage-way through the opening in said hollow shaft.

13. In an apparatus for effecting counter-current contact between fluids, a rotor having opposing face-plates, a spiral strip mounted between said face-plates to form a spiral passage-way in said rotor, means for supplying a fluid within the rotor at the center of said passage-way in said rotor, means for rotating said rotor to force said fluid to travel outwardly through the passage-way under centrifugal force, means for supplying a lighter fluid to said rotor at the outer end of said spiral passage-way under pressure sufficient to force said lighter fluid to travel inwardly through the said passage-way in counter-current to said first-mentioned fluid, at least one face-plate of said rotor being transparent to light rays, and means for directing active light rays through said transparent face-plate to the interior of said passage-way to induce reaction between the fluids therein.

14. The process of securing reaction between fluids which comprises supplying reacting fluids to the interior of a spiral passage-way while maintaining said spiral passage-way under rotation to develop centrifugal force sufficient to propel heavier fluids outwardly through said passage-way, at least one wall of said spiral passage-way being transparent to active light rays, and directing active light rays against the transparent wall of said passage-way and to the interior thereof to cause reaction between said fluids, liquid products resulting from said reaction being forced outwardly through said spiral passage-way.

15. The method of refining hydrocarbon oils which comprises supplying an aqueous reactive fluid to the center of a spiral passage-way, rotating said passage-way to secure by centrifugal action an outwardly propellant force to cause said aqueous reactive fluid to move outwardly through the passage-way and supplying the hydrocarbon oil to the outer end of said passage-way under pressure sufficient to force said oil inwardly through said passage-way to the center thereof in counter-current contact with said aqueous reactive liquid.

16. The method of refining hydrocarbon oils which comprises supplying sulphuric acid to the center of a spiral passage-way, rotating said passage-way to secure by centrifugal action an outwardly propellant force sufficient to propel said sulphuric acid outwardly through said passage-way, and supplying the hydrocarbon oil to the outer end of said passage-way under pressure sufficient to force said oil inwardly through said passage-way to the center thereof in counter-current contact with said sulphuric acid.
